UNITED STATES PATENT OFFICE

153,175

DESIGN FOR SMOKER'S TOBACCO PIPE

Harland G. Romberg, Omaha, Nebr.

Application May 2, 1947, Serial No. 138,773

Term of patent 7 years

(Cl. D85—8)

To all whom it may concern:

Be it known that I, Harland G. Romberg, a citizen of the United States of America, residing at Omaha, in the county of Douglas and State of Nebraska, have invented a new, original, and ornamental Design for Smoker's Tobacco Pipe, of which the following is a specification, reference being had to the accompanying drawing, forming part thereof.

Figure 1 is a side elevational view of a smoker's pipe, showing my new design.

Figure 2 is a top plan view.

Figure 3 is a bottom plan view.

I claim:

The ornamental design for smoker's tobacco pipe, as shown.

HARLAND G. ROMBERG.
